UNITED STATES PATENT OFFICE.

SMITH KEIGHLEY, OF PITTSBURG, PENNSYLVANIA.

FIREPROOF METAL WINDOW FRAME AND SASH.

No. 818,969.

Specification of Letters Patent.

Patented April 24, 1906.

Application filed December 21, 1905. Serial No. 292,821.

To all whom it may concern:

Be it known that I, SMITH KEIGHLEY, a citizen of the United States, residing at Pittsburgh, in the county of Allegheny and State 5 of Pennsylvania, have invented certain new and useful Improvements in Fireproof Metal Window Frames and Sashes; and I do declare the following to be a full, clear, and exact description of the invention, such as will 10 enable others skilled in the art to which it appertains to make and use the same.

This invention relates to sheet-metal fireproof windows; and one of the principal objects of the same is to provide means for reducing the friction between the sash and the window-frame and at the same time to provide means for excluding wind, snow, rain, or ice from between the sash and frame.

Another object of the invention is to provide improved means for adjusting the pulley-stiles of the window-frame to conform to the dimensions of the sash and to compensate for variations between the window frame and sash, to insure smooth operation of the 25 parts, and to prevent the binding of one part upon another.

Another object is to provide in a sheet-metal fireproof window a sash-guide to accommodate a weather-strip upon a sash and 30 to permit the free and smooth action of the strip within the guide without creating undue friction and at the same time to prevent rattling of the parts.

The foregoing and other objects are accomplished by means of the construction illustrated in the accompanying drawings, in which—

Figure 1 is a horizontal section taken through the side of a window-frame, the adjustable pulley-stiles, and one section of the sash of a metal fireproof window made in accordance with my invention. Fig. 2 is a perspective view of a short section of a sash with a guide-strip formed thereon in accordance 45 with my invention. Fig. 3 is a horizontal sectional view taken through one of the screws for adjusting the pulley-stiles and showing a portion of the window-casing and the pulley-stile.

Referring to the drawings for a more particular description of my invention, the numeral 1 designates a sheet-metal fireproof window-casing having a rectangular portion 2, designed to accommodate weights h for 50 operating sash and which fits a recess 3 in the wall of the building and extending thence

outwardly to form shoulders 3', fitted against the inner surface of the wall. The casing is formed into a molding 4, at the outer side thereof, and the edge of the sheet metal extending thence inwardly at 5, backwardly at 6, and outwardly at 7, a slight projection 8 being formed at a point to extend from bottom to top of the sash and to bear against the weather-strip and prevent the passage of air 65 or the accumulation of rain, snow, or ice at this point. At the inner side of the casing the terminal 9^x of the metal is plain, and the projection 8 may be omitted from this portion of the casing. The pulley-stiles 10 may 70 be formed of two separate portions or strips, each consisting of a strip bent to form a groove 11 for the terminal edge 9 of the casing and extending thence to form a facing for the window-frame and then bent inwardly to 75 form a guide 12 for the weather-strip upon the sash. The terminal edge of the sash-guide strip is secured to a division-strip 13, said strip extending outward to form separate sash-weight pockets 14 15, the metal being bent inwardly to form two points a b , between which the weather-strip is adapted to slide and to be guided by said points without undue friction of the parts. From the portion a the strip extends across to form the 80 other sash-guide and is bent at c in a manner similar to the bend d , and the sash-guide thence being formed into a groove or pocket for the terminal end of the front portion of the window-casing and thence extending outwardly 85 to form a terminal flange 16. In order to adjust the pulley-stiles to compensate for sashes of slightly-varying widths, a series of threaded bolts 17 pass through the face portion of the window-casing at opposite sides of the sash-grooves, said bolts extending through the 90 terminal flanges formed on the pulley-stiles and through nuts lying against and preferably secured to said flanges, said nuts being provided with an extension 18, which extends back of the pulley-stile and connects with the nut on the opposite side, forming a 95 continuous reinforcement which holds the pulley-stile stiff and rigid and which fits across the grooves or pockets.

The window-sash comprises a hollow sheet-metal oppositely-formed molding 19, intermediate grooves 20 for the glass, and the two side walls or surfaces 21 22, the wall 22 extending backward and bent upon itself, as at 100 23, to form a weather-strip adapted to fit and move freely in the sash-guides. A cross-

- strip 24 is bent into substantially U shape, and one limb of the U extends between two portions of the wall 21 and is secured therein by means of rivets 25. The opposite side of 5 this cross-strip is similarly bent, and the side wall 22 is bent around the terminal edge of the cross-strip and secured by rivets in a manner similar to the opposite side, thus forming a projecting guide e to bear against 10 the inner surface of the facing strip or pulley-stile to insure a true and smooth action of the sash, while the projection f forming the weather-strip fits one of the guides and moves freely therein.
- 15 From the foregoing it will be obvious that a sash and window casing made of metal in the form shown and described will move freely and regularly without binding and without creating undue friction against the 20 frame and that the parts will be comparatively close between the weather-strip and the window-casing to exclude the elements and that the facing-strips or pulley-strokes may be adjusted for compensating for any 25 variation in the sash with the view of insuring a smooth action and removing the liability of the binding of the various parts.
- Having thus described my invention, what I claim as new, and desire to secure by Letters Patent, is—
- 30 1. In a metal weather-strip and sash-guide, a metal strip having oppositely-disposed bearing-points extending toward each other, in combination with a metal sash having an 35 extended weather-strip f adapted to move between said bearing-points, substantially as described.
2. In a metal fireproof window, a hollow-metal window-casing, pulley-strokes secured 40 thereto, sash-guides formed in said stiles and provided with two oppositely-disposed bearing-points 8, e, in combination with a metal window-sash having one of its walls bent upon itself and inclosing a cross-strip to form
- 45 a weather-strip f to move between said bearing-points, and an oppositely-disposed flange e to bear against the face of the pulley-stile to insure smooth operation of the parts, substantially as described.
3. In a metal window, the combination of 50 a pulley-stile provided with a sash-guide having oppositely-disposed bearing-points 8, e, and an enlarged guide-chamber back of said points, and a sash-frame having an inwardly-extending weather-strip or tongue f adapted 55 to move between said bearing-points, and within the guide-chamber, and a flange e opposite the weather-strip or tongue adapted to bear against the facing of said pulley-stile, substantially as described.
4. A metal window-sash having its terminal inner edges bent to form a weather-strip f and a guide-flange e and inclosing a cross-strip 24, said parts being riveted together, in combination with a metal window-casing having 60 a sash guide or chamber into which the weather-strip fits and slides, substantially as described.
5. In a metal window, the combination of 65 pulley-strokes provided with terminal flanges 9, 16, a window-casing, bolts passing through said casing and through said flanges for adjusting the pulley-strokes to compensate for the variation in the size of sash, sash-guides formed in said stiles and provided 70 with oppositely-disposed bearing-points 8, e, and a sash having a projecting weather-strip f to fit between the oppositely-disposed bearing-points and move in the sash-guide, substantially as described.
- 80 In testimony whereof I have hereunto set my hand in presence of two subscribing witnesses.

SMITH KEIGHLEY.
